US0D1103867S

(12) **United States Design Patent** (10) Patent No.: **US D1,103,867 S**
(45) Date of Patent: ** Dec. 2, 2025

(54) **AUTOMOBILE DISPLAY PANEL**

(71) Applicant: **TOYOTA JIDOSHA KABUSHIKI KAISHA**, Toyota (JP)

(72) Inventor: **Shinsuke Ohmori**, Toyota (JP)

(73) Assignee: **TOYOTA JIDOSHA KABUSHIKI KAISHA**, Toyota (JP)

(**) Term: **15 Years**

(21) Appl. No.: **29/908,188**

(22) Filed: **Jan. 11, 2024**

(30) **Foreign Application Priority Data**

Jul. 14, 2023 (JP) ..... 2023-014627 D

(51) **LOC (15) Cl.** **12-16**

(52) **U.S. Cl.**

USPC **D12/192**

(58) **Field of Classification Search**

USPC D12/190-192, 195, 345, 415, 419

(57) **CLAIM**

The ornamental design for an automobile display panel as shown and described.

DESCRIPTION

FIG. 1 is a right, front perspective view of an automobile display panel showing my new design;

FIG. 2 is a left, front perspective view thereof;

FIG. 3 is a right, rear perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The claimed design is indicated by the relatively dark portions in the figures. The relatively light portions form no part of the claimed design.

1 Claim, 9 Drawing Sheets
